UNITED STATES PATENT OFFICE.

JACOB LEFKOWITZ, OF LONG ISLAND, NEW YORK, ASSIGNOR TO NOVEL SALES CORPORATION, OF NEW YORK, N. Y., A CORPORATION OF NEW YORK.

CHANGEABLE PRICE TAG.

Application filed March 17, 1926, Serial No. 95,339. Renewed July 6, 1927.

This invention relates to new and useful improvements in price tags applicable to merchandise displayed in shop windows and more particularly to a changeable price tag, 5 the primary object of the invention being to provide a device of this character for permanent use by the owner whereby the same may be applied to various garments at various times to display various prices, as may 10 be desired.

A further object of the invention resides in providing a tag of the character mentioned which will enable the owner thereof to insert changeable reading matter in connection with the price notations used therewith.

Still another object resides in constructing the tag and changeable elements thereof of such material as will enable the same to 20 be quickly and readily cleaned by washing so that a permanently clean tag may be had at all times.

A still further object resides in constructing the tag so that a holder is formed adapted to receive laterally and vertically moveable and changeable inserts, the lateral insert forming a limitation or stop member for the vertically movable inserts.

Still another object of the invention resides in providing a device of the character mentioned which is simple and durable in construction, inexpensive to manufacture and one which will be very useful and advantageous in trade.

With these and numerous other objects in view, my invention consists in the novel features of construction, combination and arrangement of parts as will be hereinafter referred to and more particularly pointed 35 out in the specification and claims.

In the accompanying drawing, forming a part of this application,

Figure 1 is a perspective view of a device constructed in accordance with my invention,

Figure 2 is a horizontal section therethrough, as seen on the line 2-2 of Figure 1,

Figure 3 is a similar view as seen on the 50 line 3-3 of Figure 1,

Figure 4 is a vertical section through the device, as seen on the line 4-4 of Figure 1, and

Figure 5 is a rear elevation of the device.

In describing the invention I shall refer

to the drawing in which similar reference characters designate corresponding parts throughout the several views and in which 1 designates a blank of any preferred size and shape formed preferably of celluloid or any 60 of the numerous imitations thereof, although it may be constructed of metal, wood, fibre, paper or any other desired material. Celluloid or the various compositions similar thereto and in imitation thereof is preferable 65 in view of its attractiveness, its lightness in weight and the fact that it may be used permanently and at the same time kept clean. Upon the front face of the blank adjacent the upper edge thereof is preferably printed, or otherwise impressed therein, the name of the dealer using the tag and said blank has an enlarged central portion cut therefrom to provide an opening designated by the numeral 2. Below the enlarged opening 2 and spaced therefrom, as well as being spaced from the lower edge of the blank, is formed a second cut-out portion or opening 3 which is preferably 70 elongated in a horizontal direction, as clearly shown in Figure 1 of the drawing.

Applied to the rear face of the blank 1 and spaced therefrom slightly by means of the vertical and horizontal edge-strips 4 is a back plate 5 formed of the same material as the blank 1. This back plate 5 is of the same width as the blank 1 and has its lower edge flush with the lower edge of said blank but it is shorter than said blank and forms substantially a pocket on the rear face of 80 the blank. The blank, edge-strips 4 and rear plate 5 are secured together in any preferred manner, such as by an adhesive, and a complete holder is thus formed.

The one side edge-strip terminates at its 95 lower end in a plane just above the horizontal plane of the upper edge of the opening 3 which provides a slot 6 in the one side edge of the device whereby a strip or insert 7 may be introduced therethrough so that reading 100 matter or other indicia appearing thereon may be displayed through the opening 3 in the blank 1. When so inserted, the strip or insert 7 rests upon and is guided on the lower horizontal edge-strip 4 and the movement of 105 said strip 7 is limited in one direction by the vertical edge-strip 4 on the side of the blank opposite that in which the slot 6 is formed, as appears obvious from Figure 3 of the drawing. This strip or insert 7 may con- 110

tain any desired reading matter, as stated, such as the words "Special," or "Reduced," and said strip is preferably formed of the same material as the other portions of the device.

The strip 7 fits snugly between the blank 1 and the rear plate 5 and in order to assist in the removal of said strip, the blank 5 is cut-away slightly as shown at 8 and the strip is provided adjacent its one end with an orifice which may be observed through the cut-away portion 8. Thus, the point of a pencil or other instrument may be inserted in the orifice 9 and said strip readily withdrawn when desired.

My improved tag also contemplates use of a plurality of additional strips designated by the numeral 10 which are insertable vertically in the pocket formed between the blank 1 and the back plate 5. These strips are adapted to be introduced through the opening formed in the upper end of the pocket and said strips, which are also formed of the same material as the other portions of the tag, have printed, impressed or embossed thereon numerals which are preferably in contrasted color to the coloring of the strips, so as to be displayed through the opening 2 in the blank 1. These strips 10 which bear the numerals are of such width that a predetermined number of the same may fit in the pocket between the two vertical edge strips 4 and the lower edges of said strips are adapted to rest upon the upper edge of the laterally movable strip 7. Obviously, these strips 10 may be interchanged to display various numerals and correspondingly various prices for the garments to which the tag is applied for display. Each strip 10 is adapted to contain one numeral, although more than one numeral may be applied thereto and, in fact, reading matter or other indicia may be applied to these strips as desired for display purposes.

When properly supported in position in the pocket of the device so that the lower edges of the strips 10 rest upon the upper edge of the laterally movable strip 7, the upper ends of said strips 10 project above the upper edge of the rear plate 5, as clearly shown in Figures 4 and 5 of the drawing and as said strips 10 fit snugly in place, I prefer to form openings or orifices 11 therein adjacent the upper ends so that the point of a pencil or other instrument may be inserted therein and said strips readily withdrawn from the pocket by forcing upwardly thereon.

It will be observed from the foregoing description that I have provided a changeable price tag wherein certain elements are removable through vertical movement and a certain element removable through a lateral movement, the laterally movable element acting as a support or limitation for

the vertically movable elements. This particular construction affords simplicity in construction and corresponding cheapness in manufacture. While the horizontally or laterally movable element is disclosed herein with certain reading matter adapted to be displayed and co-related to the data appearing on the vertically movable strips, it will be understood that a blank strip, if desired, may be used as a support for the vertically movable strips. The construction enables the strips to be readily removed and interchanged when desired so that a permanent price tag is thus produced.

From the foregoing description of the construction of my improved device, the operation thereof and application to use will be readily understood, and it will be seen that I have provided a simple, inexpensive and efficient means for carrying out the objects of the invention. While I have particularly described the elements best adapted to perform the functions set forth, it is obvious that various changes in form, proportion and in the minor details of construction may be resorted to, without departing from the spirit or sacrificing any of the principles of the invention.

Having thus described my invention what I claim is:

1. A tag including a holder, removable display strips slidable vertically therein and an additional removable strip slidable laterally on said holder in the same vertical plane with the aforesaid strips and adapted, when in place, to support and limit the movement of said first mentioned strips in one direction.

2. In a tag, a holder comprising a blank having display openings therein, a pocket formed on the rear face of said blank, removable strips slidable vertically through in said pocket adapted for display through one of the aforesaid openings and a laterally slidable and removable strip in said pocket for display through the other of said openings, said laterally slidable strip being adapted, when in place, to support said first mentioned strips and limit the movement of the same in one direction.

3. In a tag, a holder comprising a blank having upper and lower display openings formed therein, a rear plate secured to and spaced from the rear face of said blank to form a pocket on the latter, the upper end of the pocket being open, one side edge of said pocket having a slot therein in alignment with the aforesaid lower opening, changeable strips adapted for introduction through the open end of said pocket and movable vertically in the latter for display through the upper opening, and an additional strip adapted for introduction to said pocket through the aforesaid slot for display through the lower opening, said additional

strip being movable laterally and when in place adapted to support said first mentioned strips and limit the movement thereof in one direction.

5 4. In a tag, a holder, said holder comprising a blank provided with upper and lower display openings, edge-strips applied to the rear face of said blank along the bottom and side edges thereof, a rear plate applied to said edge-strips and forming therewith a pocket on said blank, the upper edges of said side-strips and rear plate terminating short of the upper edge of said blank and forming the opening for said pocket, a plurality of changeable strips adapted for insertion through the opening in said pocket

and movable vertically therein, said strips being adapted for display through the upper of the aforesaid openings in said blank, one side edge of said pocket being provided with 20 a slot, an additional strip adapted for insertion through said slot and movable laterally in said pocket for display through the lower opening in said blank, one side edge-strip limiting the movement of said additional strip in one direction and said additional strip, when in place, forming a support and limitation for the movement of said first mentioned strips in one direction. 25

In testimony whereof I affix my signature.

JACOB LEFKOWITZ.
